UNITED STATES PATENT OFFICE.

ALBERT P. DAVIS, OF DEPOSIT, NEW YORK.

PHOTOGRAPHIC-FILM HOLDER.

1,130,152.

Specification of Letters Patent.

Patented Mar. 2, 1915.

Application filed March 19, 1914. Serial No. 825,730.

To all whom it may concern:

Be it known that I, ALBERT P. DAVIS, a citizen of the United States of America, residing at Deposit, in the county of Broome and State of New York, have invented certain new and useful Improvements in Photographic-Film Holders, of which the following is a specification, reference being had to the accompanying drawings.

This invention relates to improvements in apparatus for developing, fixing and washing photographic films and particularly to improvements in devices for holding the film during the carrying out of the developing, fixing and washing operations (and, of course, during any other time that it may be desired to hold the film stretched taut); and an object of this invention is to improve the quality of the developed or finished film and to increase the number of such films finished in a given time (as per hour), and thereby to increase the income derived from the work of developing films.

In the drawings illustrating the principle of this invention and the best mode now known to me of applying that principle, Figure 1 is a perspective view of my new film-holder; Fig. 2 shows my new film-holder inverted and in place in a developing tank; Fig. 3 is a detail showing the base-connector of one of the posts; Fig. 4 is a detail showing in vertical section a two-part base-connector; and Fig. 5 is a perspective view of the film-holding clip.

The film-holder consists essentially of the base-board *a*, the fixed post *b*, the movable post or stretcher *c* and the connector *c'* for connecting the base of the latter to the base-board. Each end of the baseboard *a* is formed with lengthwise extending slots, the slots *d* at one end being longer than the slots *e* at the other end. Of course, the number of slots *d*, *e*, formed in the base-board need be limited by only the width of the base-board; but generally it will be found that a pair of slots *d* and the corresponding pair of slots *e* will suffice for the ordinary user. Such an arrangement of slots will permit short films *f* to be treated together; or a longer film may be wound between the four posts, keeping exposed to the outside the sensitized face. The lower end of the post is enlarged to provide a base-connector *c'* for connecting the post to the baseboard *a* and is for this purpose formed with a rigid base *g'* and with a pair

of channels or recesses *g* the bottom walls *g''* of which are flanges which bear against the bottom of the parts of the baseboard adjacent to the slots *d*, *e*. The walls of the latter fit in the channels *g* and the posts are 60 slidable along the same, so that the posts *b*, *c*, may be readily engaged with and disengaged from the baseboard and the distance between the two posts *b*, *c*, may be 65 varied at will, not only for the purpose of stretching the film taut, but also for adjustment for different lengths of film. The fit of the base-connector *c'* on the base-board *a* is such that the posts are very slightly 70 tiltable toward each other for a purpose hereinafter explained.

I have found that when the ordinary film is slightly wetted at its ends, while the latter lie in overlapping contact with one 75 another and are held pressed together, the ends will adhere firmly, so that the film will retain after immersion the form of a closed band, which permits the finished film to be handled with very little trouble. In order to bring suitable pressure upon the overlapping ends, a U-shaped clasp or clip *j* is 80 provided, which clip is resilient and fits snugly upon the post *b* and brings suitable pressure upon the overlapping ends *f'* of 85 the film. As is clearly shown in Fig. 1, these ends are interposed between the post *b* and the inner face of the clip *j*.

In using my new film-holder the film is bent around the posts *b*, *c* in the manner 90 shown in Fig. 1; and the overlapping ends *f'* are engaged and held by the clip *j* which fits snugly upon the post *b*. The film *f* is then stretched taut by sliding the movable post or stretcher *c* along the slot *d*. When 95 the film is sufficiently stretched, it will be found that the tension of the film has tilted slightly the post *c* (for clearness of illustration the tilting is exaggerated in Fig. 2) so that the rigid base *g'* and the flanges *g''* 100 bind upon or bite (so to speak) into the parts *h*, *i*, or the base-board *a* opposed thereto somewhat after the manner of a bureau-drawer which sticks in its guideways; and in this way the post *c* is automatically secured firmly in place. The film-holder is then inverted and placed in the developing solution contained in a shallow receptacle or so-called tank *k*, the ends of the film-holder resting upon the edge or rim portion 105 of the latter. Between the film ends, which are held by the clip *j* pressed tightly to

gether and against the post *b*, the solution enters in such amount as to wet the film ends slightly and the latter will be found to adhere firmly to each other. This is an important feature of this invention. Again, it is seen that the film is immersed edgewise in the developing solution, from which it results that every part of every film is acted upon uniformly and equally throughout the whole extent of its surface. Any sediment or salts formed will readily drop from the film to the bottom of the tank. After having been subjected to the action of the developing solution for a sufficient length of time, the operator grasping the film-holder at the reduced or narrow portion *m* raises the same from off the tank *k* and next immerses the film in the fixing bath contained in a receptacle similar in all respects to the tank *k*. After the image has been fixed upon the film, the operator removes the film-holder to the washing tank, where the film is thoroughly cleaned.

The slots *e* are formed in the base-board for the purpose of enabling the post *b* to be readily put in place and as readily removed therefrom. Instead of the slot *e*, a hole may be formed in the base-board (as at *a'*, Fig. 2) and the post *b'* may then be formed with a stud or stem *b''* adapted to fit snugly in the hole *a'*; but for cheapness of manufacture, it is preferable to give all the posts the same shape. Again, they are then interchangeable and therefore handy to use.

In order to prolong the life of the device, the posts *b*, *c* are preferably made of acid-resisting material, such as glass, porcelain, hard rubber or like material which will not be corroded by exposure to the liquids used in developing and fixing the films; and it is likewise preferable to make the clip *j* of similar (non-corrosive) material.

By the use of my new film-holder the quality of the product is improved; for, the films need not be touched or handled after mounting them upon the posts *b*, *c*; and spots, stains, scratches and the like upon the film are entirely obviated. The operator need never soil his fingers with any of the solutions used; and the films, when finished, are in the best possible condition for printing. Every part of each film gets exactly the same treatment,—the same amount of developing, fixing and washing. The number of films which may be treated and finished is increased greatly by the use of my new film-holder; for, the films may be mounted upon the latter in the minimum time and the films may be quickly transferred from one bath or solution to the next. The use of my new film-holder minimizes the amount of attention required from the operator and thereby permits the operator to have more time out of the dark-room than he has been

able to obtain under systems of developing heretofore in use. It is only necessary for the operator to mount his films upon the film-holder, invert the latter, immerse the films in a shallow tank or like receptacle and, after the proper time has elapsed, to remove the films from the first or developing tank and immerse them in the second or fixing tank; and, after the proper time allowed for fixing the image has elapsed, to remove the films from the fixing tank and immerse the films in the washing tank. In this way an operator using five film-holders each capable of carrying a pair of films can treat ten films at the same time. Furthermore, the films being immersed edgewise in the solution, are held therein in the best possible way to secure uniform action by the solutions to which they are subjected (developing solution, fixing solution). My new film-holder is furthermore adapted for use in either a small gallery or a large gallery; it can be used in the average small dark room and in connection with tanks set on ordinary shelves. Tanks best adapted for use with my film-holder are readily emptied and rinsed. A system in which my new film-holder is used requires less room than does any other system of as great capacity and is more economical in its use of solutions, a larger yield of finished film being obtained per gallon of bath. Furthermore, the percentage of perfect films is greater in a system using my film-holder as a part thereof. The contrivance itself is cheap and durable, consisting of substantially only three principal parts which in ordinary use are practically indestructible,—the base board (which may be of wood) and the two posts (which are preferably of non-corrosive material); by the use of acid-resisting material for the posts, the necessity of washing the posts is avoided and at the same time the length of life of such posts is greater than that of corrodible material, even when the latter are carefully cleansed, all of which attention requires time and labor and involves considerable expense in keeping the apparatus in proper working condition. My new film-holder is extremely simple in construction and this simplicity conduces to cheapness of manufacture and to relatively low cost of first installation or equipment of a gallery with my film-holder and also insures that the cost of upkeep or expense for repairs will be small. It is to be observed that my new film-holder is devoid of springs, cogs, wheels or like machinery, which are susceptible to corrosion, require constant care and attention, particularly in the matter of cleaning, lack durability and involve expenditure of much money for replacing and repair of parts. Again, my new film-holder conduces to speed in the work and to increase in the production. Several tanks and

a corresponding number of base-boards may be used at the same time by the same operator. Thus, while one set of frames are being loaded, another set may be in the developing tank, still another set in the fixing tank and a fourth set in the washing tank. The production of finished films thus is made to depend upon the ability of the operator.

10 In Fig. 4 there is shown a two-part base-connector. The lower end of the post c'' is formed with a rectangular base piece n which lies within a box-like frame or connector o the sides o' of which are adapted to 15 fit slidably in the slots e' formed in the baseboard a . The top of the connector o is provided with a circular hole o^x through which projects the portion of the post c'' that lies above the base n , which itself is held between the top of the connector o and the top of the baseboard a . The connector o is open on two sides, so that its sides o' may be slipped readily into the slots e' formed in the baseboard a ; and the depth of the sides o' of the connector o is such that when the connector with its post is placed in the slots (as is shown in Fig. 4), the inwardly turned flanges o'' formed at the bottom of the connector bear against the bottom of the baseboard a , whereby the connector is given a sliding fit in the baseboard.

I claim:

1. A photographic film-holder comprising a baseboard; and a pair of film-holding posts one of which is slidable along said baseboard and is provided with a base-connector which has flanges that bear against the bottom of said baseboard and also includes a rigid base that bears against the top of said baseboard; said slidable post having a close fit on said baseboard and being only slightly tilttable toward the other post to permit the tension of the stretched film to cause said rigid base and flanges to bind upon the faces of the baseboard opposed thereto and thereby to lock automatically.

cally said slidable post in its adjusted position on said baseboard solely by the binding action of said base and flanges thereon.

2. A photographic film-holder comprising 50 a baseboard; and a pair of film-holding posts one of which is slidable along said baseboard and is provided with an integral base-connector which is slidably mounted in said baseboard and is formed with a channel 55 within which fits closely a wall of said baseboard; said slidable post having a close fit on said baseboard and being only slightly tilttable toward the other post to permit the tension of the stretched film to cause the top 60 and bottom walls of said channel to bind against the top and bottom, respectively, of said baseboard and thereby to lock automatically said slidable post in its adjusted position along said baseboard solely by the binding action 65 thereon of the walls of said channel.

3. A photographic film holder comprising a baseboard; a pair of film-holding posts one of which is slidable along said 70 baseboard and is provided at its base with flanges which have a close sliding fit on said baseboard; said slidable post being only slightly tilttable toward the other post to permit the tension of the stretched film to cause 75 said flanges to bind upon the faces of the baseboard opposed thereto and thereby to lock automatically said slidable post in its adjusted position along said baseboard solely by the binding action of said flanges 80 thereon; and a clasp shaped to fit snugly upon one of said posts and to fasten thereto the end portions of the film bent there-around.

Signed at Deposit, New York, this sixteenth day of February, A. D. 1914, in the presence of the two undersigned witnesses.
